Primary Examiner—Holly H Baynham*(74) Attorney, Agent, or Firm*—Smith IP Services, P.C.(57) **CLAIM**

The ornamental design for a reversible asymmetric hanger for suspending objects such as wires, strips and loops, as shown and described.

DESCRIPTION

FIG. 1 shows an isometric view of the new design for a hanger apparatus;

FIG. 2 shows a first side view of the new design;

FIG. 3 shows a second side view of the new design;

FIG. 4 is an opposite side view of the view shown in FIG. 2;

FIG. 5 shows a top side view of the new design;

FIG. 6 shows a bottom side view of the new design;

FIG. 7 is an environmental second side view thereof;

FIG. 8 is a second environmental, second side view thereof;

FIG. 9 is an environmental side view opposite the views shown in FIGS. 3, 7 and 8; and,

FIG. 10 is a second environmental side view opposite the views shown in FIGS. 3, 7 and 8.
